CLAIM

The ornamental design for an optical information reader, as shown and described.

DESCRIPTION

FIG. 1 is a front, right-side, top perspective view of a first embodiment of an optical information reader, showing the new design;

FIG. 2 is a front view thereof;

FIG. 3 is a rear view thereof;

FIG. 4 is a top plan view thereof;

FIG. 5 is a left-side view thereof;

FIG. 6 is a right-side view thereof; and

FIG. 7 is a bottom plan view thereof.

FIG. 8 is a front, right-side, top perspective view of a second embodiment of an optical information reader, showing the new design;

FIG. 9 is a front view thereof;

FIG. 10 is a rear view thereof;

FIG. 11 is a top plan view thereof;

FIG. 12 is a left-side view thereof;

FIG. 13 is a right-side view thereof; and,

FIG. 14 is a bottom plan view thereof.
